UNITED STATES PATENT OFFICE.

PAUL PRYIBIL, OF NEW YORK, N. Y.

MACHINE FOR DRILLING TO PATTERN.

SPECIFICATION forming part of Letters Patent No. 447,014, dated February 24, 1891.

Application filed December 31, 1890. Serial No. 376,342. (No model.)

To all whom it may concern:

Be it known that I, PAUL PRYIBIL, of the city and county of New York, in the State of New York, have invented a new and useful 5 Improvement in Machines for Drilling to a Pattern, of which the following is a specification.

My invention relates to an improvement in machines for drilling to a pattern, and, while 10 adapted to use in connection with any class of work where it is desirable to drill a series or group of holes in accordance with a predetermined pattern, is particularly well adapted for drilling the plates in pianos.

15 A practical embodiment of my invention is represented in the accompanying drawings, in which—

Figure 1 represents the machine in front elevation. Fig. 2 represents the same in side 20 elevation, and Fig. 3 represents a top plan view showing the hanger in section.

A drill-spindle A is supported in sliding adjustment within a pair of bearings b and b', fixed to a plate B. The plate B is pivotally secured at or near its lower end to an intermediate plate C, whereby it, together with the spindle carried thereby, may be rocked into position to present the cutter or drill a obliquely to its work. Provision is made in 25 the present instance for locking the plate B in the desired adjustment by a clamp-screw b², which extends through an elongated slot b³ in the plate B, and into the plate C; to which the plate B is pivoted.

30 The plate C has a vertically-sliding movement between a pair of guide-cheeks d, fixed to a hanger D, which forms the support for the drilling mechanism. A clamp-screw E, extending through an elongated slot e in the hanger D and into the plate C, serves to lock the said plate in the desired vertical adjustment. To the hanger D, preferably near its lower end, as shown, there is secured a bracket-arm F, having an adjustment laterally with 45 respect to the hanger, the adjustment being conveniently provided for, as shown in the present instance, by an elongated slot f, formed in the bracket-arm, through which a clamp-screw projects into the hanger.

50 Through the end of the bracket-arm F there is formed an opening for the reception of a reciprocating sleeve or holder G, within which

a guide-pin H is seated. The holder G is provided below the bracket-arm with an abutment g, between which and the lower side of the arm a spring g' is located, the tension of which tends to hold the holder in depressed adjustment. The guide-pin H is adjustable within the holder, provision being made in the present instance for locking it in the desired extended adjustment by a set-screw h, extending through the holder into contact with it. The lower end of the pin H is made conical, as shown at h', for the purpose of rendering the pin self-centering within the perforation in the pattern.

In the present instance I have shown a single lever for simultaneously lifting the drill-spindle and holder G, and to this end I have provided the lever I, fulcrumed upon a link i, pivotally secured at its lower end to a lug i' on the plate B, the lever I being connected intermediate of its ends with the spindle. A spring K tends to hold the lever normally elevated. An auxiliary lever L is fulcrumed 75 upon a link l, pivotally secured at its lower end to a lug l' on the bracket-arm F and connected intermediate of its ends with the sliding holder G. The free end of the lever L is connected with the operating-lever I, preferably by a flexible connection l'.

From the above construction and arrangement it follows that when the lever I is depressed the spindle A will be lowered, thereby throwing the cutter or drill a into contact 85 with its work, and at the same time the holder G will be free to move downwardly, carrying the guide-pin H into contact with one of the holes of the pattern. The guide-pin and cutter may be lifted out of engagement with the pattern and work by raising the lever I.

It is obvious that the lever I might be operated by a treadle instead of by the hand by connecting it with a treadle in any well-known or approved manner, and also that the auxiliary lever L for elevating the guide-pin might be operated independently of the lever I.

The table supporting the pattern and work 100 is represented by M, and is mounted upon suitable rollers m, which run upon tracks n, fixed on a sub-table N. The sub-table N is also provided with suitable rollers n', which

run upon tracks *o*, fixed upon a suitable support *O* and extending in a direction at right angles to the tracks *n* on the sub-table *N*. It is intended that the tables *M* and *N* shall be mounted so as to move with great facility, and because of the freedom of the table *M* to move in either direction at pleasure, the pattern *P* thereon and the work *p* secured thereon in the desired position relative to the pattern may be brought into adjustment so that each one of the holes *p'* of the pattern may fall directly beneath the axis of the guide-pin *H*. When so adjusted, the cutter or drill *a* will be in position over the work to form a hole therein corresponding to that hole in the pattern in which the guide-pin *H* is engaged.

The conical shape of the end of the pin *H* will tend to center the pin within the perforation as the pin is depressed, as it will move the table by its pressure against the side of the hole. The spindle *A*, which carries the cutter *a*, is provided with a driving-pulley *Q*, adapted to be driven by a belt from any suitable source of power. (Not shown herein.)

What I claim as my invention is—

1. In a machine for boring or drilling, the combination, with the drill or cutter and means for operating it, of a pattern corresponding to the work to be done, and a guide-pin bearing a predetermined relation to the cutter and adapted to engage the different points of the pattern and thereby determine the position of the cutter relative to the work, substantially as set forth.

2. The combination, with a drill or cutter, means for operating it, and a suitable support for it, of a guide-pin having a predetermined position relative to the cutter, and a pattern and work support, the said work-support being free to move in different directions to bring any point in the pattern beneath the guide-pin, substantially as set forth.

3. The combination, with the drill or cutter, means for operating it, and a guide-pin having a position predetermined with respect to the cutter, of a pattern and work supporting

table mounted upon rollers and free to move in one direction upon a track, and a sub-table upon which said track is supported, the said sub-table being free to move upon a track in a direction at right angles to the movement of the first-named table, substantially as set forth.

4. The combination, with a suitable support, a vertically-sliding plate secured thereto, and a laterally-tilting plate pivoted to the vertically-sliding plate, of a drill or cutter and its holder mounted in suitable bearings attached to said tilting plate, a laterally-adjustable arm or bracket secured to the support, a vertically-movable guide-pin mounted in said arm or bracket, a pattern and work support, and means for adjusting the pattern and work support to bring the pattern into the desired position relative to the guide-pin, substantially as set forth.

5. The combination, with a suitable support, a drill or cutter, and its holder mounted in said support and having a limited longitudinal movement, of a supporting-arm secured to said drill-support, a vertically-yielding guide-pin mounted in said arm, a lever for operating said pin, and an operating-lever common to the drill-spindle and pin-operating lever for simultaneously operating the drill and pin, substantially as set forth.

6. The combination, with the drill or cutter, its spindle, and the support in which the spindle is mounted, of a supporting-arm fixed in lateral adjustment with respect to the spindle-support, a guide-pin secured in yielding adjustment to the arm and provided with a conical end, a pattern provided with holes adapted to receive the conical end of the guide-pin, and a support for the pattern free to move in different directions with respect to the guide-pin to bring any one of the holes of the pattern into alignment with the guide-pin, substantially as set forth.

PAUL PRYIBIL.
